UNITED STATES PATENT OFFICE.

FREDERICK H. HOLBROOK, OF BOSTON, MASSACHUSETTS.

DESIGN FOR A VAMP-STIFFENER.

SPECIFICATION forming part of Design No. 12,548, dated October 25, 1881.

Application filed August 11, 1881. Term of patent 14 years.

To all whom it may concern:

Be it known that I, FREDERICK H. HOLBROOK, of Boston, in the county of Suffolk and Commonwealth of Massachusetts, have 5 invented and produced a new and original Design for Vamp-Stiffeners for Shoes, Slippers, &c., of which the following is a specification, reference being had to the accompanying drawing, forming a part thereof, in which the figure is a representation of the plain crescent shape of my design.

The leading features of my design are the crescent shape of the body and the central raised setting with the two side patterns in 15 corresponding settings, as shown in the drawing.

A is the body of the stiffener, which is bent to conform to the contour of the instep of the shoe, and is of a crescent shape, either plain 20 in outline, as in the figure, or ornamental. This body is attached to the shoe by any suitable means, and has upon its upper surface the central raised setting, B, upon either side of which are the settings or embossed figures C and D.

E is a border of wire-work pattern, which 25 extends around the edge of the body A.

F F are suitable triangular ornaments in wire-work, which are placed at each extremity of the crescent, while the spaces between the settings and each side of the figures C and D are occupied by the embossed figures G, the whole presenting the appearance shown in the drawing.

I claim—

A design for a vamp-stiffener, consisting of 35 the crescent-shaped body A, bent to conform to the contour of the instep, having upon its upper surface the raised figures B C D, border E, triangular ornaments F F, and embossed figures G, substantially as shown and described. 40

In testimony whereof I have signed my name to this specification before two subscribing witnesses.

FREDK. H. HOLBROOK.
